(57) **CLAIM**

The ornamental design for a compression wound dressing, as shown and described.

DESCRIPTION

FIG. 1 is a top perspective view of an embodiment of a compression wound dressing according to the design.

FIG. 2 is a bottom view thereof;

FIG. 3 is a first lateral side view thereof;

FIG. 4 is a top view thereof;

FIG. 5 is a second lateral side view thereof;

FIG. 6 is a back view thereof; and,

FIG. 7 is a front view thereof.
